DISCHARGE DEVICE FOR FINELY DIVIDED
FIBROUS MATERIAL FROM A PRESSURE
SYSTEMHjalmar S. Messing, New York, N. Y., assignor
to American Defibrator, Inc., New York, N. Y.,
a corporation of Delaware

Application May 26, 1949, Serial No. 95,561

2 Claims. (Cl. 92—6)

1

This invention relates to an improved device for continuously discharging solid material, more especially finely divided or comminuted fibrous material suspended or entrained in a fluid medium in a pressure system, while minimizing the loss of fluid medium and drop in pressure in the system. The present invention is a continuation-in-part of my co-pending application Serial No. 547,686 filed August 2, 1944, now abandoned and is particularly advantageous for discharging fibrous stock from mechanical abrading or defibrating apparatus wherein the defibration of the raw material is carried out in an atmosphere of steam at temperatures considerably above 212° F. and at pressures from approximately 100 to 200 lbs. per square inch. Since such defibrating apparatus is operated continuously it is essential to provide a discharge device for withdrawing fibrous stock which device will not deleteriously affect the efficient operation of the apparatus by requiring the supply of excessive amounts of steam or by allowing a pressure drop within the apparatus.

In one well-known type of defibrating apparatus, the material to be treated, such as wood chips, bagasse, bamboo, sawmill waste and the like, is continuously fed into a mechanical defibrator or abrader in which steam is maintained at a pressure and temperature sufficiently high to soften the ligneous material of the middle lamella which binds the fibers together. The material being refined is maintained at elevated temperature and pressure while being subjected to the abrading action of relatively rotating refining members. Since the binding effect of the middle lamella of the fibers has been reduced by the high temperature of the steam, a minimum expenditure of power is required to separate the fibers and a minimum of breakage of individual fibers occurs, thereby producing a homogeneous defibrated product.

Heretofore, the refined fibrous stock has been discharged from the defibrator through an outlet duct controlled by a pair of alternately actuated valves arranged in series within the duct. While this arrangement has operated satisfactorily to discharge fibrous stock from the defibrator without concomitant waste of steam and drop in pressure within the system, the valve controlled outlet mechanism is characterized by a number of distinct disadvantages. For example, a suitable system of cams, rollers and associated movable valve mechanism are required for rapid opening and closing and alternate actuation of the valves. Moreover, the

rapid operation of the valves results in wear and necessitates frequent inspection, dismantling of the parts and replacement of the valve cones and seats in order to maintain the efficiency of the refining unit. Furthermore the discharge opening could not be changed without removal and replacement of parts.

Accordingly, it is an object of the present invention to provide a device of the character indicated which may be readily adjusted for variable discharge and which is adapted for continuously delivering fibrous material from a pressure system while substantially maintaining a pressure seal thereon without occasioning excessive wear and replacement of parts.

Another object of the invention is the provision of a discharge device which is constructed and arranged in such a manner as to minimize the possibility of clogging.

An additional object of the invention is the provision of a discharge device having relatively adjustable rotary impingement members serving to dissipate the energy of the fiber jet as it passes through the device and simultaneously operating to break up residual bundles or agglomerations of fibers, thereby resulting in further refining of the fibers as they pass through the discharge device.

A further object of the invention is the provision of a discharge device which may be successfully employed in connection with digesters or cookers in continuous pulp digesting processes.

A particular object of the invention is the provision of an improved discharge device over that disclosed in my co-pending application Serial No. 547,686 filed August 2, 1944, now abandoned, of which latter application, the present application constitutes a continuation-in-part.

The features and advantages of the present invention will be readily apparent in the course of the following detailed description taken in connection with the accompanying drawing which illustrates a preferred embodiment of the invention, and wherein:

Fig. 1 is a plan view, partially in cross-section showing the improved discharge apparatus associated with a defibrating machine;

Fig. 2 is a cross-sectional view on an enlarged scale showing a preferred embodiment of the discharge apparatus itself;

Fig. 3 is a view similar to Fig. 2, but showing another embodiment of my invention;

Fig. 4 is a cross-sectional view taken on line 55 4—4 of Fig. 3;

Fig. 5 is a cross-sectional view taken on line 5-5 of Fig. 3;

Fig. 6 is an elevational view, partly in section on line 6-6 of Fig. 7, of a third embodiment of a discharge device;

Fig. 7 is an end elevation of the device of Fig. 6 with the control wheel removed;

Fig. 8 is an elevational view on an enlarged scale of the adjustable rotor element of the device showing the knurled segments of the conical impingement members; and

Fig. 9 is an enlarged fragmentary detail illustrating the cooperation between one of the rotary impingement members and its respective surrounding housing portion to define an adjustable path of flow through the device.

Referring to the drawings, reference character 10 designates generally a feeding device. This includes a hopper 12 to which is supplied ligno-cellulose material, preferably in the form of wood chips. A twin-screw conveyor 14 located at the bottom of the hopper carries the chips into a cylinder 16 within which is located a piston which is reciprocated by means of a piston rod 18 connected to a cross-head 20. A connecting rod 22 is connected between the cross-head 20 and a crank 24, the latter being rotated through suitable gearing 26 by means of an electric motor 28.

The interior of the left-hand portion of cylinder 16 is formed as a plurality of frusto-conical sections 30 and opens into the upper part of a receiver 32. A conduit 34 connects the lower part of the receiver with the center of the housing 36 of a rotary disc refiner. A screw conveyor 38 driven by an electric motor 40 is disposed within the conduit 34.

A stationary disc 42 is located within the housing 36 and is formed with a central opening in alignment with the conduit 34. A rotary disc 44 is mounted on a shaft 46 which is rotated by a motor 48 through a multiple belt drive 50. The clearance between the discs 42 and 44 may be adjusted by means of a handwheel 52. The housing 36 is provided with a tangential outlet opening 54. Steam under suitable pressure is admitted to the receiver 32 through the conduit 56 and to the refiner through the conduit 58.

The apparatus so far described is a standard commercial product and is substantially shown in Asplund Patents No. 2,008,892 and No. 2,145,851.

Connected to the outlet 54 of the refiner is a conduit 60 which leads to the cylindrical casting 62 of the improved discharge device. As shown in Fig. 2, a nozzle 64 may be located between the outlet 54 and the conduit 60, although it is to be understood that the nozzle may be omitted.

A conduit 68 communicates with the cylinder 62 and leads to a cyclone 70 or other suitable receptacle. Located in the cylinder 62 between the conduits 60 and 68 is one or more transverse disc-shaped partitions 72 provided with central openings 74. Between the partitions and between the forward partition and the inlet end of the cylinder 62 are liners 76. Both the partitions and the liners are preferably made from a very hard and wear-resisting material having an abrasive surface, such as Carborundum.

A shaft 78 is rotatably mounted in combined radial and thrust bearings 80 and 82 carried in pedestals 84 and 86, respectively, and in a slide bearing 88 supported in the rear end wall 90 of the cylinder 62. A stuffing box 92 is provided

where the shaft extends through the wall 90. Affixed to the forward end of this shaft is one or more Carborundum discs 94, the number of discs being equal to the number of partitions 72. At the outlet side of the rearmost disc the shaft 78 preferably carries a baffle disc 96, which may be of Carborundum or steel.

The bearings 80 and 82 are shiftable axially in their pedestals 84 and 86 by means of a handwheel 98 so as to vary the axial clearance between the rotary discs 94 and the stationary partitions 72. A pulley 100 is mounted on the shaft 78 and is driven through a multiple belt drive 102 by an electric motor 104. A water pipe 106 may communicate with the left-hand end of the cylinder 62 as by being connected to a suitable aperture in the end wall 90.

The above described device operates as follows:

Suitable ligno-cellulose material such as wood in the form of chips is introduced into the hopper 12, the chips being conveyed by the twin-screw conveyor 14 into the cylinder 16 and as the piston reciprocates therein it compresses the chips so as to form a suitable solid plug in the left-hand end of the cylinder. This plug is able to hold the steam pressure within the apparatus and thus prevent the escape of any substantial amount of steam at the feed end. The conical sections 30 prevent the plug from being blown back by the steam pressure as the piston reciprocates to the right. When the piston again moves to the left additional chips have been fed into the cylinder and these are compacted between the piston and the plug, with the result that the plug is advanced to the left into the receiver 32. As soon as the end of the plug is relieved of its confinement as it enters the relatively large receiver, it breaks up and the individual chips fall to the bottom of the receiver. From here they are moved by the screw conveyor 38 to within refiner housing 36. Steam is admitted through the conduits 56 and 58 at a pressure such that the temperature is at or above that at which the middle lamella which bind the fibers of the wood together is markedly softened.

The chips in this heated condition are introduced between the discs 42 and 44 and due to rotation of the latter the fibers are separated from each other. A minimum amount of power is required for this operation due to the fact that the middle lamella has lost its adhesive property due to the temperature. Moreover, the fibers may be separated by the discs with a minimum of damage to the individual fibers.

From the housing 36 the fibers in separated state pass through the outlet 54 to within the conduit 60. If the nozzle 64 is provided this introduces a certain resistance to flow, thus reducing the rate at which steam escapes from the housing into the conduit 60.

From the conduit 60 the stock is introduced into the cylinder 62 and strikes the first rotating disc 94. This disc imparts a rotary movement to the stock and consequently centrifugal force aids in causing it to flow outward against the liner 76. Here its direction of flow is abruptly changed and the stock is caused to flow around the outer edge of disc 94 and thence must pass radially inwardly to the central openings 74 in the stationary partition 72. Centrifugal force tends to retard flow in this direction. From here the stock strikes the next rotating disc 94 and must

pass outwardly around its periphery and thence inwardly to the central opening 74 in the next stationary partition.

Due to the fact that the partitions, liners and discs are made of an abrasive material, such as Carborundum, they have a further refining action on the stock and consequently tend to separate any bundles of fibers which may have passed through the defibrating machine.

Stock passing through the central opening 74 in the left-hand partition strikes the baffle 96 which is provided chiefly for preventing the stock from impinging directly around the bearing 88. From the left-hand end of the cylinder 62 the stock passes through the conduit 68 to the cyclone 70. If desired, water may be introduced through the conduit 106 to aid in slushing the stock out of the cylinder 62 and into the cyclone and it also serves to condense steam.

The velocity of stock and steam which passes through the discharging device may be controlled by varying the speed of rotation of the discs 94 and the clearance between these discs and the partitions 72 so as to pass just the amount discharged from the defibrator, and consequently the escape of excess steam may be prevented. The greater the speed of the discs, the greater will be the centrifugal force tending to retard passage of the stock from the outer regions of the cylinder to the central openings 74 in the stationary partitions. Likewise, reducing the clearance between the discs and the partitions will also reduce the flow. Also, the provision of additional discs and partitions would have the same effect.

In the embodiment illustrated in Figs. 3, 4 and 5 a nozzle 110 is located within the conduit 60 which is connected to the outlet 54 of the defibrator. An annular space 112 is provided between the nozzle and the conduit 60, into which water may be introduced tangentially through the conduits 114 and 116, as is shown more particularly in Fig. 4. An annular injector nozzle 118 is provided between the inner end of the nozzle 110 and a partition 120.

Mounted within the casing 62 on the shaft 78 of this embodiment are three rotary discs 96a, which are similar to the discs 96 of Fig. 2, but as shown are provided with convex peripheries. Ahead of the first disc 96a is a stationary liner 122 formed with a funnel-shaped aperture 124. Behind this disc is a stationary partition 126 which is similar to the partition 72 in Fig. 2, except that the central aperture therein is formed with a convex surface.

Next to the partition 126 is a disc-shaped member 128 having a central aperture with which communicates a tangential passage 130, as is shown more particularly in Fig. 5. This passage is connected to a conduit 132 through which water may be supplied. On the other side of the disc 128 is a partition 134, which is located ahead of the next rotary disc 96a. A similar partition 136 is located between the second and third rotary discs, while another similar partition 138 is located behind the last disc.

Between the various partitions and in radial alignment with the rotary discs are annular liners 140, the openings through which are provided with concave surfaces. The partitions, rotary discs and liners are preferably made of abrasive material, such as carborundum.

The shaft 78 may be moved axially in a manner similar to that shown in Fig. 2 in order to vary the clearance between the rotary and sta-

tionary members, and may be driven in a similar manner.

This embodiment operates as follows:

The stock discharged from the defibrator 5 through the outlet 54 enters the nozzle 110 which, due to its decreasing diameter, introduces a certain resistance to flow and increases the velocity of the stock. Water supplied through the conduits 114 and 116 is caused to flow through the nozzle 118 by injector action and consequently the pressure of the water supplied through these conduits need not be as high as the steam pressure in the defibrator. The water introduced through the nozzle 118 is mixed with the stock and aids in the further refining of the latter as it passes through the discharge device.

The mixture of water and fibers passes around the rotary discs and through the apertures in the stationary partitions in the manner as described in connection with the first embodiment. The abrasive nature of the discs, partitions and liners serves to further refine the stock, and the pressure is reduced in the same manner as above described.

Sufficient water may be introduced through the conduit 132 between two of the rotary discs 96a to form a suspension of the fibers, which aids further in the refining thereof as they pass the subsequent rotating discs. The mixture of fibers and water may be discharged into a cyclone or other suitable receptacle in the same manner as above described.

Actual tests have proved that the above described device due to the relatively narrow and tortuous passages, restricts the rate of flow sufficiently so that the quantity of steam escaping is maintained within reasonable and economic limits, while clogging of the passages by the stock is prevented due to the rotation of the discs. In addition, the abrasive action is such as to separate into individual fibers substantially all of any remaining fiber bundles.

Referring now to Figs. 6 to 9 of the drawings, the discharge device includes an inlet conduit 210 which leads to the casing 211 of the device. As shown in Fig. 6, a nozzle 212 may be disposed in the inlet conduit 210 adjacent the casing 211. A shaft 213 is rotatably mounted in combined roller and thrust bearings 214 carried on supports 215. A combined slide bearing and stuffing box 216 is provided in the rear end wall 211a of casing 211 where the shaft 213 extends through said rear wall.

Affixed to the forward end of shaft 213 within casing 211 is one or more rotary impingement members 217 and 218 which are preferably formed with rearwardly divergent or conical impingement surfaces in order to utilize the centrifugal force exerted upon the fiber jet passing through the discharge device in such a manner as to offer minimum resistance to the flow of the fibrous stock and to prevent clogging of the device. The foremost rotary member 217 may be threaded upon the front end of the shaft 213 as shown at 219 and may be secured in place by inserting a suitable tool in a hole 220 extending transversely through said member adjacent the forward end thereof. Rotary member 218 is preferably frusto-conical in shape and may be secured on shaft 213 in any suitable manner.

Rotary members 217 and 218 cooperate with internal liners 217a and 218a to provide for variable discharge through the device by axial displacement of shaft 213, as will be more fully described hereinbelow. The angular inclination of

the surface of the liners 217a and 218a is preferably slightly less than that of the impingement surfaces of rotary members 217 and 218 respectively in order to effect positive closure of the passage through casing 211 when required. As best shown in Figs. 8 and 9 the impingement surfaces of rotary members 217 and 218 are provided with a plurality of spaced grooves 225 defining therebetween knurled segments 226 and 227 respectively. The presence of grooves 225 serves to increase the centrifugal force exerted on the fiber jet as it is whirled against the rotary impingement members 217 and 218. Simultaneously the knurled segments 226 and 227 serve to break up and further refine any residual fiber bundles, clusters or agglomerations in the fibrous stock passing through the device. The angularly inclined surfaces of casing liners 217a and 218a may also be knurled, if desired. The material leaves casing 211 by means of a discharge conduit 228 which may be connected to any suitable receiver (not shown). The liners 217a and 218a and the rotary impingement members 217 and 218 may be made from suitable abrasive material, such as Carborundum, as an alternative to being knurled, in order to achieve the desired refining action.

In order to vary the discharge rate through the device means are provided for varying the axial clearance between the rotary impingement members 217 and 218 and the casing liners 217a and 218a by axial displacement of the shaft 213. Bearing supports 215 are mounted on a carriage or base plate 230 which is slidably received between bearing members 231 fixed to a frame or channel members 232. An upright plate 233 is fixed to channel member 232 and carries the threaded shaft 234 of a handwheel 235, the inner end of said shaft being secured to the outer bearing support 215. The rate of discharge through the device may thus be varied by adjusting the handwheel 235 to vary the clearance between the rotary impingement members 217 and 218 and the casing liners 217a and 218a. The forward displacement of shaft 213 may be limited by means of an adjustable stop-bolt 236, as shown in Fig. 6.

In order to prevent damage to the rotary impingement members and the casing liners if some foreign material such as a nail should become lodged between said members and liners provision is made for automatic retraction of shaft 213. Handwheel shaft 234 carries a fixed collar 237 and a compression spring 238 is interposed between outer bearing support 215 and said collar. Excessive pressure on shaft 213 beyond the limit of tension of spring 238 will result in temporary retraction of said shaft and the rotary member 217 and 218 until the foreign object is blown out of the casing through outlet conduit 228.

A pulley 240 is mounted on shaft 213 which may be driven from a suitable power source through a multiple belt drive 241. A water pipe 242 may communicate with the inlet end of the casing 211 by means of a jacket 243 and inlet openings 244 to aid in flushing the material through the discharge device.

The arrangement shown in Figures 6 to 9 presents significant advantages over the disclosure in Figures 1 to 5 wherein variable passage of material through the discharge device is provided by a series of relatively adjustable discs and liners. In the aforementioned application the control of clearance between the discs and liners is not positive and the flow of material through

the central aperture of each liner is resisted by centrifugal force which frequently results in clogging.

However, by reason of the improved construction and arrangement of the present invention and the rearwardly divergent impingement surfaces of the rotary members 217 and 218, the centrifugal force generated within the device is utilized for assuring continuous flow therethrough.

In operation the suspended or entrained fibrous material enters the device through inlet conduit 210. If the nozzle 212 is provided a certain resistance to flow occurs and the rate at which steam enters casing 211 is reduced. Also the presence of nozzle 212 concentrates the stream of fibrous stock into a jet which impinges against the pointed end of rotary member 217. Rotary member 217 imparts a rotary movement to the fibrous stock and generates centrifugal force aided by the grooves 225. Because of the rearwardly divergent impingement surfaces of the rotary members 217 and 218 and their cooperation with the liners 217a and 218a which are complementary in contour to said impingement surfaces, the discharge device advantageously utilizes the centrifugal force generated therewithin to promote the flow of fibrous stock therethrough and prevent clogging. Simultaneously the knurled segments 226 and 227 serve to break up and further refine residual fiber bundles and clusters.

Since certain modifications may be made in the discharge device of the present invention without departing from the scope thereof, it is intended that all matter contained in the foregoing description and shown in the accompanying drawing be interpreted merely as illustrative and not in a limiting sense.

What is claimed is:

1. A device for continuously discharging finely divided fibrous material from a pressure system while substantially maintaining a pressure seal thereon, comprising a casing having a restricted inlet opening provided with a flaring portion extending away from the opening, a shaft rotative within the casing, said shaft being longitudinally adjustable and carrying a plurality of spaced conical members, one of said conical members being a cone having an apex located in said flared portion and spaced from the wall thereof, the second conical member being frustro-conical, each of the conical members having at least a portion of its surface roughened and grooved, the apex portion of the cone that is located in the flared part of the inlet opening being relatively smooth and free of the roughness and grooves, the interior of the casing being provided with a plurality of spaced liners maintained in end-to-end abutment, one of each of said liners extending about and being spaced from the periphery of each conical member, one of the liners being formed with a recess in one end of greater diameter than the conical members, which recess is situated at a location to form a chamber located intermediately of the conical members.
2. A device for continuously discharging finely divided fibrous material from a pressure system while substantially maintaining a pressure seal thereon comprising a casing having an inlet passage having converging walls leading to a restricted opening, the passage flaring beyond the opening, a shaft rotative within the casing, said shaft being longitudinally adjustable and carrying a cone at one end, said cone having a pointed

- 70 75

apex defining the end of the shaft, said apex being located in and surrounded by and spaced from the flared portion of the wall of the inlet passage, a frustro-conical member fitted on the shaft and spaced from the cone, the cone and frustro-conical member each having at least a portion of its surface roughened and grooved, the apex portion of the cone that is located in the flared part of the inlet passage being relatively smooth and free of the roughness and grooves, the interior of the casing being provided with a plurality of spaced liners maintained in end to end abutment, one of each of said liners extending about and being spaced from the cone and frustro-conical member respectively, one of the liners being formed with a recess in one end of greater diameter than the cone and frustro-conical member, which recess is situated at a location to form a chamber located intermediate of the cone and conical member.

HJALMAR S. MESSING.
